UNITED STATES PATENT OFFICE.

FRANK S. CHOPIESKA, OF LA CROSSE, WISCONSIN.

PISTON RING.

Application filed May 15, 1922. Serial No. 560,966.

To all whom it may concern:

Be it known that I FRANK S. CHOPIESKA, a citizen of the United States, residing at La Crosse, in the county of La Crosse and 5 State of Wisconsin, have invented a new and useful Piston Ring, of which the following is a specification.

This invention has reference to piston packing, and aims to provide a novel form 10 of piston ring to insure a fluid-tight connection between the ring and wall of the cylinder in which the same is moving.

An object of the invention is to provide a 15 piston ring including a plurality of sections, said sections being constructed to prevent movement of one section with respect to the other section.

A still further object of the invention is 20 the provision of a lock at the ends of one of the sections, whereby when the ends are moved into engagement with each other, they will be interlocked to insure a fluid-tight connection.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

Referring to the drawing:

35 Figure 1 is a perspective view of a piston ring constructed in accordance with the present invention.

Figure 2 is a perspective view of one section of the ring.

40 Figure 3 is a perspective view of the outer section of the ring.

Figure 4 is a fragmental detail view disclosing the interlocking ends of the outer section.

45 Referring to the drawing in detail, the device embodies an inner ring section 5 and an outer ring section 6, the inner ring section 5 being split and provided with interlocking ends 7.

50 The inner ring section is formed with peripheral flanges 8 which are disposed in

spaced relation with each other to provide a clearance for the outer ring section 6, which is shown as fitted in the inner ring section 5. One end of the inner section is 55 formed with spaced tongues 9 disposed adjacent to the edges thereof, which tongues are designed to move within the cut out portions 10 formed in the peripheral flanges 8 to lock the sections together in a manner to prevent 60 uneven expansion of the ring.

A pin 11 extends from the periphery of the inner section and is adapted to contact with one end of the outer ring section to prevent movement of the outer section circumferentially of the inner section to eliminate any possibility of the split portions of the sections aligning to allow fluid to pass therethrough.

From the foregoing it will be seen that 70 I have provided a ring wherein the inner or supporting section thereof is exceptionally wide, lending resiliency to the ring structure causing the outer section to be forced into close engagement with the wall of the 75 cylinder in which the ring is positioned.

It might be further stated that due to the interlocking ends of the inner section, the inner section is held in a true circular formation to prevent scoring of the cylinder 80 by one of the ends moving radially beyond the opposed end.

Having thus described the invention, what is claimed as new is:—

A piston ring comprising an inner split 85 ring section and an outer split ring section, the inner section having circumferential flanges, the outer ring section being supported by the inner section and disposed between the flanges, one of the ends of said inner section having tongues, the flanges adjacent to the opposite end having openings 90 to receive the tongues, and means for preventing movement of one section circumferentially of the opposed section. 95

In testimony that I claim the foregoing as my own, I have hereto affixed my signature in the presence of two witnesses.

FRANK S. CHOPIESKA.

Witnesses:

Jos. V. NIGRO,
L. KLEEBER.
